United States Patent Office

Des. 188,647
Patented Aug. 16, 1960

188,647

FLAT WOVEN FLOOR COVERING OR SIMILAR ARTICLE

Alan Brown, Higganum, Conn., assignor to Congoleum-
Nairn Inc., Kearny, N.J., a corporation of New York

Filed Oct. 22, 1958, Ser. No. 53,096

Term of patent 14 years

(Cl. D92—4)

The figure is a plan view of a flat woven floor covering, showing my new design, with a full repeating unit being disclosed between the dashed lines thereof.

I claim:

The ornamental design for a flat woven floor covering or similar article, substantially as shown and described.
